UNITED STATES PATENT OFFICE

MAX M. ORR AND CHESTER E. DOXEY, OF MINNEAPOLIS, MINNESOTA

DESIGN FOR A DISPLAY CASE

Application filed July 13, 1929. Serial No. 32,045. Term of patent 7 years.

To all whom it may concern:

Be it known that we, MAX M. ORR and CHESTER E. DOXEY, both citizens of the United States, of No. 224 Hennepin Avenue, of the city of Minneapolis, county of Hennepin, and State of Minnesota, have invented a new, original, and ornamental Design for Display Case, of which the following is a specification, reference being had to the accompanying drawing, forming part thereof.

The figure is a perspective view of a display case, showing our new design.

We claim:

The ornamental design for a display case, as shown.

CHESTER E. DOXEY.
MAX M. ORR.
